UNITED STATES PATENT OFFICE

EDWARD J. LANG, OF RIVERSIDE, ILLINOIS

FUSE PANEL

Application filed December 17, 1928. Serial No. 326,499.

The present invention has for its object to produce a simple and novel panel adapted to support numerous fuses of different capacities, the construction being such that the clips for the fuses may be easily removed and replaced and be interchangeable with each other.

The various features of novelty whereby my invention is characterized will herein-
10 after be pointed out with particularity in the claims; but, for a full understanding of my invention and of its objects and advantages, reference may be had to the following detailed description taken in connection with
15 the accompanying drawings, wherein:

Figure 1 is a top plan view of a fuse panel arranged in accordance with my invention; Fig. 2 is a bottom plan view; Figs. 3 and 4 are sections, on an enlarged scale, taken re-
20 spectively on lines 3-3 and 4-4 of Fig. 1; Fig. 5 is a top plan view of one of the units detached from the panel; and Fig. 6 is a section on line 6-6 of Fig. 5.

Referring to the drawings, 1 and 2 are two
25 longitudinal frame members connected together by a plurality of broad cross members of which three, indicated at 3, 4 and 5 are shown. The endmost cross members of the frame are located at some distance inwardly
30 from the ends of the frame.

The frame is covered with a slab of insulating material which, in accordance with one feature of my invention, is composed of a large number of sections or pieces of which
35 there are a plurality of groups of longitudinal pieces. In the assembled structure illustrated there is a cross piece of insulating material between the central group of longitudinal pieces and each of the two end groups,
40 and a third cross piece at the outer end of one of the endmost groups of longitudinal pieces. The cross pieces are secured to the longitudinal frame elements, conveniently
45 by means of screws 8, and the longitudinal pieces 6 are secured to the cross elements of the frame by detachable fastenings, conveniently screws 8. The cross pieces are thinner than the longitudinal pieces so that when a
50 heavy bus bar 9 is laid upon and secured to each cross piece, its top face will be flush with

the top faces of the longitudinal pieces. Each bus bar has a socket 10 extending down from the same through the underlying piece of insulation, for the purpose of receiving
55 the end of a cable or other heavy conductor.

Overlying and secured to each longitudinal piece 6 of insulating material is a pair of clips for receiving and holding a fuse. Fuse clips vary in size and shape according to the capacity of the fuse to be mounted therein.
60 Where there are many circuits distributed from a panel there will be a wide variation in the selection of fuses, according to the use to which the panel is to be put. It is therefore desirable that the fuse clips, regardless
65 of their capacity, be interchangeable with each other so that the panel may be equipped with any desired selection of fuses. I therefore so proportion the clips and so drill the panel, that the clips for a fuse of any desired capacity may be mounted anywhere on the panel.

In the arrangement shown, there are clips for four different sizes of fuses. One clip of each pair, indicated at 11, 12, 13 and 14 projects beyond the corresponding end of the longitudinal piece of insulating material on which it is mounted, and extends across the adjacent bus bar. Each of the clips, 11 to 14, is fastened to the underlying bus bar by
70 means of a screw 15. Each clip is also secured to the underlying longitudinal piece of insulating material 6 by means of a pair of screws 16. Each longitudinal piece 6 is also provided with a screw hole 17 into which may
75 be entered another screw 18 in the case of long clips such as the clips 11 and 12. The second clip of each pair, namely those indicated at 21, 22, 23 and 24, lies wholly upon
80 the corresponding longitudinal piece of insulating material and is provided with a socket 25 extending from the same through the insulating material for the purpose of receiving a cable or heavy wire on the rear of
85 the panel. Each of the clips 21 to 24 is held in place by means of a pair of screws 26. Each piece 6 is also provided with additional
90 holes 27 to receive additional screws 28 in the case of long clips, such as the clips 21 and 22.
95

The drilling of the panel and the lengths of the clips is such that any pair of clips may be removed and another pair of clips, for a fuse of a different capacity, be substituted therefor. Also, by removing the screw 15 that secures one of the clips of each pair to a bus bar, as well as the two screws 8 that hold the corresponding longitudinal piece of insulating material in place, the entire piece or block of insulating material, with the overlying, attached pair of clips, may be removed without disturbing the fastenings between the clips and the supporting piece. Therefore, the user of the panel may be provided with 10 additional blocks or pieces 6 each having thereon a pair of clips so that, whenever the capacity of a fuse is to be changed, an entire section of the panel may be removed and replaced by another section.

It will thus be seen that I have provided a simple and novel fuse panel that may be made of any size, by simply using the proper frame and the proper number of sections or pieces of insulating material; one in which 20 clips for different sizes of fuses are interchangeable; and one from which a pair of clips may readily be removed to make room for another pair. Therefore the panel is not only convenient but it consists of simple elements that may be combined to produce 25 panels of various sizes.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:—

1. The combination with a panel drilled along two parallel rows to receive fastenings for fuse clips, and a plurality of pairs of clips for fuses of different sizes made in such 40 lengths that the clips of each pair will be properly spaced to receive the corresponding fuse when secured in any pair of holes in said rows.

2. In a device of the character described, 50 a panel comprising numerous pieces of insulating material, a single cooperating pair of fuse clips on each of said pieces, and means supporting all of said pieces in such a manner that any of the pieces may be removed independently of the others.

3. In a device of the character described, a frame, a slab of insulating material mounted on the frame and consisting of numerous individual pieces arranged side by side, means 60 detachably connecting each of said pieces to the frame independently of the other pieces, and a pair of fuse clips mounted on each of said pieces and removable therewith.

4. A device of the character described comprising a frame consisting of longitudinal

and cross members, a slab of insulating material overlying said frame, said slab consisting of groups of longitudinal pieces overlying and detachably secured to said cross members of the frame and interposed cross pieces secured at their ends to the side elements of the frame, bus bars overlying and secured to said cross pieces, and a pair of fuse clips overlying and secured to each of said longitudinal pieces, one clip of each pair being detachably secured to one of the bus bars.

In testimony whereof, I sign this specification.

EDWARD J. LANG.
